[57] ABSTRACT

A turbine having a plurality of pressure attenuation plenum chambers. These chambers are located adjacent the vanes of a turbine thereby relieving the excess pressure by distributing it through a series of apertures in the plenum chamber walls.

TURBINE PRESSURE ATTENUATION PLENUM CHAMBERS

BACKGROUND OF THE INVENTION

This invention relates generally to turbines and, more particularly to plenum chambers located within the turbine to eliminate pressure distortion.

A conventional gas turbine engine generally comprises of a compressor, a combustion products generation means, a turbine wheel, a duct connecting these elements and a shroud surrounding the turbine wheel. In this type of gas turbine engine pressurized air is supplied to the combustor and supports combustion of fuel to generate an annular hot gas stream. This hot gas stream, generally speaking, then drives a turbine which powers a compressor for pressurizing the air delivered to the combustor. The hot gas stream may then power a second turbine or be discharged from a nozzle to obtain an energy output from the engine.

It is well known that the efficiency of such a gas turbine engine is related to the operating temperature of the turbine and that the efficiency may be raised by increasing the operating temperature. A further consideration in the efficiency of such a turbine is the elimination of a pressure build up within the turbine which causes distortion thereof. With regard to the operating temperature much time and energy has been expended in the construction of complex cooling systems for the turbine itself. However, little consideration has been given to the elimination of the pressure build up within the turbines which also constitutes an essential factor in turbine efficiency.

SUMMARY OF THE INVENTION

The turbine of this invention utilizes plenum chambers adjacent the turbine wheel in order to overcome the problems encountered heretofore by reducing the excess pressure within the turbine.

Chambers have been constructed within the turbine having a plurality of strategically located apertures therein in order to relieve this excess pressure build up. With the plenum chambers located adjacent the turbine wheel the circumferential pressure distortion is greatly reduced and the gas path air then "breathes" to a common pressure.

It is therefore an object of this invention to provide turbine pressure attenuation plenum chambers which substantially reduce the pressure distortion within a turbine.

It is another object of this invention to provide turbine pressure attenuation plenum chambers which utilize conventional, currently available components which lend themselves to standard mass producing manufacturing techniques.

For a better understanding of this invention, together with other and further objects thereof, reference is made to the following description taken in connecting

with the accompanying drawing and its scope will be brought out in the appended claims.

DESCRIPTION OF THE DRAWING

5 The only FIGURE of this drawing is a side elevational view shown partly in cross-section of the turbine pressure attenuation plenum chambers of this invention.

DESCRIPTION OF THE PREFERRED EMBODIMENT

10 Reference is now made to the only FIGURE of the drawing which represents a side elevation view of the turbine pressure attenuation plenum chambers 10 of this invention. The turbine 12 generally comprises of 15 an air compressor, combustion products generation means, at least one turbine wheel having a plurality of blades 14 and stationary vanes 15, a duct connecting these elements and a rotating hub 16 surrounding blades 14 and vanes 15 of turbine 12.

20 Hub 16 supports and rotates with turbine blades 14. Plenum chambers 20 and 22 are located opposite one another adjacent stationary vane 15 with plenum chamber 20 located above vanes 15, while the other chamber 22 is approximately at the midpoint thereof. 25 Each plenum chamber 20 and 22 is triangular in configuration and has strategically placed apertures 24 therein. Upper chamber 20 having three such apertures, with lower chamber 22 having two such apertures 24. It is critical that apertures 24 be positioned adjacent vanes 15 as shown in the FIGURE in order to 30 lower the circumferential pressure distortion and provide a gas path within turbine 12. By eliminating this excess pressure, turbine efficiency is greatly increased.

35 Although this invention has been described with reference to a particular embodiment, it will be understood to those skilled in the art that this invention is capable of a variety of alternate embodiments within the spirit and scope of the appended claims.

40 I claim:

1. In a turbine having a plurality of blades and vanes and a shroud surrounding said blades and vanes, the improvement therein comprising a means defining first and second plenum chambers located adjacent said vanes for reducing circumferential pressure distortion of said turbine, said first plenum chamber positioned above said vanes, said second plenum chamber positioned at substantially the midpoint of said vanes, said first plenum chamber having a plurality of apertures 45 therein and said second plenum chamber having a pair of apertures therein wherein said apertures in said first plenum chamber oppose said apertures in said second plenum chamber.

50 2. In a turbine as defined in claim 1 wherein there are three apertures in said first plenum chamber.

55 3. In a turbine as defined in claim 2 wherein each of said plenum chambers are of a triangular configuration.
